UNITED STATES PATENT OFFICE.

JOHN LANE, OF HOLLY, MICHIGAN.

MOLD FOR FENCE-POSTS.

972,699.

Specification of Letters Patent. Patented Oct. 11, 1910.

Application filed January 22, 1910. Serial No. 539,449.

To all whom it may concern:

Be it known that I, JOHN LANE, a citizen of the United States, residing at Holly, county of Oakland, State of Michigan, have 5 invented a certain new and useful Improvement in Molds for Fence-Posts, and declare the following to be a full, clear, and exact description of the same, such as will enable others skilled in the art to which it pertains 10 to make and use the same, reference being had to the accompanying drawings, which form a part of this specification.

This invention relates to molds for fence posts and similar cylindrical structures.

15 It has for its object a mold adapted to be used for the construction of a fence post in the place it is to occupy, and consists essentially of a sheet metal casing without hinge, but split along one side from end to end, and 20 provided along the edge with means by which the opening may be closed and the entire mold brought into closed relation and held in such closed relation while the cement or other material of which the post 25 is constructed is placed in the mold and tamped, after which the mold is opened and sprung away from the finished post, which is left standing in place.

In the drawings:—Figure 1, is a side elevation showing the mold prepared to receive 30 the cement filling. Fig. 2, is a section showing the top end of the mold and the funnel used in connection therewith. Fig. 3, is a section showing the bottom end of the mold 35 with the tamping device in place inside the mold. Fig. 4, is a cross section at the line 4—4 of Fig. 3. Fig. 5, shows the clip used to hold together the edges at the bottom end of the mold.

40 The mold 1 is made of comparatively thin sheet metal stiffened and strengthened at its edges 2 and 3 with angle irons 4 and 5 which extend from end to end of the mold. Preferably the mold is made to correspond with 45 the ordinary fence post, larger at that end which is intended to be at the bottom than it is at the top. A clip 6 with forks 7 adapted to straddle the joined angle bars 4 and 5 is placed in position to hold the bottom end 50 or the large end of the mold in place. The mold is set upright in the post hole and arranged in the position that the post is to have when finished. A funnel with three or four external legs 10 is placed with the mouth of 55 the funnel inside the mold and with the legs 10 outside the mold at the top end. A spud

11 having a perforated head and a hollow handle 12 is dropped into the mold, and the cement material in a semi-dry condition, dry enough so that it will not run easily, is 60 poured into the mold and pounded down with the spud. The spud is made with a hollow handle and a hollow head in order that a reinforcing rod 13 may be inserted through the spud and its handle, dropped to 65 the bottom of the post with the end extending up as high as may be desired, and the reinforcing iron is held in place by the spud itself, and because it engages through the spud and its handle it does not obstruct the 70 constant and proper pounding down of the material in the mold. The part of the mold above the ground is held together by clips: wire hooks or eyes 14 are inserted into the 75 mass of the material at suitable places, the projecting part of the eye reaching through between the edges of the mold, and they may be put in place anywhere that may be desired along the extent of the opening. The material of the post is of a consistency such 80 that it will not escape through the opening, and the slight rib or ridge made along the side is immaterial and harmless. After the material has been put in place the funnel 85 may be at once removed. The mold should be left in place until the cement sets, the time depending on the character of the cement.

This mold may be built in place rapidly with material that is delivered into the funnel from a wagon, and the mold, when loosened from the post and lifted so that its bottom end rises above the surface of the ground, may generally be sprung apart 90 enough to free the mold entirely from the 95 post, or if at any time it is difficult to spring the mold sufficiently for this purpose, the mold may be lifted over the top easily.

What I claim is:—

1. A mold for fence posts, having in combination a sheet metal form having one side vertically apertured throughout its length, reinforcing angle irons attached to each edge of said apertured portion, with a flange of each extending outwardly from the plane 105 of the periphery of the sheet metal portion, a vertically extending clip provided with a plurality of rigid jaw portions located at intervals therealong, adapted to engage the outwardly flanged portions of said angle 110 irons to hold them and thereby the adjacent edges of the sheet metal form in desired re-

lation to one another, and a hollow handled tamping device adapted to engage within said form, substantially as described.

2. A mold for fence posts, having in combination a laterally apertured sheet metal form, the edge portions on each side of the aperture being outwardly flanged, reinforcing angle irons attached to each flanged edge portion, and a rigid clip member of substantially the same length as said apertured portion, said clip member being provided at intervals along its length with jaw portions adapted to engage firmly about the projecting edge and reinforcing parts of the mold

and to hold the same against spreading 15 under the pressure of a mass of contained material, and being adapted to be subsequently removed from its clamping position when the release of the sheet metal form from about the contained material is desired, substantially as described. 20

In testimony whereof, I sign this specification in the presence of two witnesses.

JOHN LANE.
